UNITED STATES PATENT OFFICE.

LARS S. ENGESET, OF SEATTLE, WASHINGTON.

WATER WHEEL.

Application filed April 21, 1923. Serial No. 633,814.

To all whom it may concern:

Be it known that I, LARS S. ENGESET, a citizen of the United States, and a resident of Seattle, King County, Washington, have 5 invented certain new and useful Improvements in Water Wheels, of which the following is a specification.

This invention relates to water power devices and more particularly to devices of 10 that character commonly known as water wheels and which are adapted, when partly submerged in flowing water, to be revolved and to transmit power through their supporting means for the purpose of driving 15 machinery or for doing other work.

It is the object of this invention to provide a water wheel with means in connection therewith whereby the speed of the wheel will be increased and additional power produced thereby. More specifically, the object 20 of the invention resides in the provision of a water wheel having a plurality of spokes, each comprising relatively movable sections, one of which carries a float and the other 25 supports a propeller and wherein means is provided for operating the propellers to add to the driving power of the wheel by 30 movable movement of the outer spoke section under the lifting influence of the floats as they enter the water.

Other objects of the invention reside in the details of construction of the various parts of the wheel and in the means whereby it is supported functionally in position. In accomplishing these and other objects of the 35 invention, I have provided the improved details of construction, the preferred forms of which are illustrated in the accompanying drawings, wherein—

40 Figure 1 is a side elevation of a water wheel constructed and supported in accordance with the present invention.

Figure 2 is a transverse, sectional view of the same taken on the line 2—2 in Figure 1.

45 Figure 3 is a detail view illustrating an alternative type of construction.

Figure 4 is a partial view of still another construction.

50 Figure 5 is a sectional view of the same. Referring more in detail to the several views of the drawings, wherein like reference numerals designate the same or like parts, 1 designates a horizontal base frame which may be supported on piles 2 or in any 55 other suitable manner within a stream of

flowing water and 3 designates a swinging frame that is pivotally fixed at one end, as designated at 4, to the frame 1 and is supported at its other end by means of a shaft 5 equipped with a turning wheel 6 at its 60 upper end whereby it may be revolved to raise or lower that end of the frame 3, the post 5 being threaded at its lower end into a sleeve 7 that is pivotally fixed onto frame 1.

65 The frame 2 comprises parallel opposite side beams between which a wheel supporting shaft 8 extends. This shaft is revolved in bearings 9 fixed to the said side beams and at one end has operative driving connection with a power transmission shaft 10 which may be extended as a driving means for machinery which it is desired to operate by the wheel. The hub 12 of the water wheel is keyed to the shaft 8 and has a plurality of radially extending spokes mounted 70 therein at equally spaced apart intervals, each spoke comprising a tubular inner section 14 that is fixed solidly in the hub and an outer section 15 that is telescopically slidable into and from the inner section. The outward movement of the spoke sections 15 within their respective inner sections is limited by means of stop plates 16 fastened to their inner ends by bolts 17 and which 75 engage with nuts 18 through which the sections slide and which are threaded into the outer ends of the section 14. The spoke sections 15 are normally retained extended by means of spring arms 20 that are fastened 80 to the inner spoke sections 14 with their outer ends connected with pins on the outer spoke sections of the spokes.

85 Fixed to the outer end of each spoke section 15 is a float 25, here shown to consist of 90 hollow metal tanks that are tapered toward their opposite ends and extended in the plane of the wheel in order that they will pass through the water with the least resistance. Mounted on the inner section of 95 each spoke is a propeller 26, each with a supporting shaft 27 mounted rotatively in bearings 28 on the spoke and equipped with a driving gear 29 that meshes with a rack surface 30 formed on the outer movable section 100 of the spoke; the connection being such that movement of the outer spoke section into or from the inner section will cause rotation of the propeller which will tend to drive the wheel in the direction of the flow of 105 110

water. Assuming that the wheel is so constructed, it would be used in the following manner:

A frame 1 would be mounted on a suitable supporting foundation in a stream of flowing water and the frame 3 so adjusted that the lower half of the water wheel would be below the water surface. The force of the current against the floats would cause the wheel to be revolved and this will bring the floats successively into the water. At the time the floats enter the water their supporting sections 15 are held in extended position by means of the spring arms 20 but as they are immersed the lifting effect of the water against them causes them to move inwardly toward the center of the wheel. This movement by means of the connecting gearing causes the propellers to be revolved in the water to drive the wheel forwardly, thus increasing the speed of the wheel and the amount of power that may be derived therefrom.

As the floats are raised from the water the spring arms 20 move the supporting spoke sections 15 to their extended position and retain them in this position until the floats again enter the water. Power for driving machinery or for other work may be derived from the water wheel by connection with the shaft 8 and while I have illustrated but one wheel on the shaft 8, it is readily apparent that any desired number could be connected therewith so that an unlimited amount of power could be obtained.

In Figure 3 I have illustrated an alternative construction wherein each spoke of the water wheel is equipped with two driving propellers. In this type of construction, brackets 40 are fixed to the outer ends of the spoke sections 14 and extend about the floats to the outer sides thereof and at these ends are equipped with propellers 41 that are alined with the propellers of the inner set. The slidable spoke sections 15 are equipped with extensions 42 that project beyond the drums and are geared, as at 43, to mesh with gears 44 fixed on the supporting shafts 45 of the propellers 41. In this construction the operation is the same as previously described and the propellers work together to increase the driving action of the wheel.

In Figures 4 and 5 is illustrated a construction wherein the propellers are geared up to revolve at a high rate of speed. In this construction the propeller shaft gears 29 are small, and mesh with large gears 50 supported on shafts 51 in bearings 52 at the end of sections 14. Small gears 53 are fixed to the shafts 51 in mesh with rack surfaces 30 of sections 15. With this construc-

tion, movement of flats inwardly causes the propellers to be driven at a high speed.

It is readily apparent that such wheels could be made in different sizes with various numbers of spokes without departing from the spirit of the invention, and that various means of support could be provided according to the character of the wheel and the stream in which it is used.

Having thus described my invention, what I claim as new therein and desire to secure by Letters Patent, is:—

1. A water wheel of the class described, comprising a supporting shaft, a wheel fixed on the shaft having a plurality of radially extending spokes, each with telescopically mounted outer section floats, fixed to the outer sections of the spokes, propeller wheels fixed to the inner spoke sections and means for revolving the propeller wheels by inward movement of the outer spoke sections under the lifting influence of the floats.

2. A water wheel of the class described, comprising a supporting shaft, a wheel fixed to the shaft having a plurality of radially extended spokes, each with an outer section movable into and from a fixed inner section, means for yieldingly retaining the outer sections of the spokes extended, propeller wheels mounted on the inner sections of the spokes, floats fixed to the outer ends of the movable spoke sections and means operatively connecting the slidable spoke sections with their corresponding propeller wheels whereby the latter will be revolved to drive the water wheel by the inward movement of these spoke sections under lifting action of their floats.

3. A device of the class described, comprising a base frame, a wheel supporting frame adjustable vertically on the base frame, a power shaft supported by the swinging frame, a water wheel fixed to the power shaft having a plurality of radially extending spokes, each with an outer section telescopically movable into and from a fixed inner section, spring arms fixed to the wheel and engaging bosses on the outer sections to retain them normally extended, propeller wheels mounted on the inner sections of the several spokes, each with a driving shaft and a gear wheel fixed to the shaft, floats fixed to the outer ends of the movable spoke sections and rack surfaces formed on the movable spokes meshing with the propeller driving gears, whereby inward movement of the movable spoke sections under lifting influence of their floats will effect rotation of the propellers for the purpose set forth.

Signed at Seattle, King County, Washington, this 13th day of April, 1923.

LARS S. ENGESET.
